UNITED STATES PATENT OFFICE.

BERNHARD SUMMERFIELD, OF CHICAGO, ILLINOIS.

LOCK.

952,480.

Specification of Letters Patent. Patented Mar. 22, 1910.

Application filed April 3, 1909. Serial No. 487,778.

To all whom it may concern:

Be it known that I, BERNHARD SUMMERFIELD, a subject of the Czar of Russia, residing at Chicago, in the county of Cook 5 and State of Illinois, have invented certain new and useful Improvements in Locks, of which the following is a specification.

My invention relates to locks, and more particularly to that class of locks embodying a cylinder adapted to screw within portions of a bolt cage, and carrying tumbler pins, and a barrel, in which a key is inserted, rotatable within the cylinder upon the correct positioning of the tumbler pins 15 by the irregular edges of the key.

The object of my invention is to provide a cylinder barrel having a key receiving slot of a novel shape whereby two sets of tumbler pins may be employed, and where- 20 by to render more difficult the insertion of a wire or other instrument, with which to pick the lock.

A further object of my invention is to provide means for securing the cylinder from removal, except when the barrel is unlocked and rotated, other than the set screws 25 ordinarily employed, and also means with which the bolt sweep may engage, thus insuring the cylinder against removal should 30 the door to which it is applied, be open.

These objects and numerous apparent advantages I attain by the structure shown in the accompanying drawing, in which—

Figure 1 is a longitudinal sectional view 35 taken through the cylinder and barrel on the line of the central portion of the barrel key slot, the barrel being locked. Figs. 2 and 3 are end elevations thereof respectively illustrating the operating parts located 40 therein and removed therefrom. Fig. 4 is a front elevation thereof. Fig. 5 is an elevation of the cylinder locking pin, and Fig. 6 is an elevation of the key formed to fit the barrel slot.

Referring to the drawings, I have shown 45 a cylinder 1 threaded for a short distance from its inner end and provided upon its outer end with an outstanding circular flange 2. Within the base of cylinder 1 is 50 arranged the barrel 3 to the inner end of which is secured a gear 4 meshing with a gear 5, which latter gear 5 carries the bolt sweep 6 rotatable upon the screw 5^a securing one end of the bridge plate 7 to the inner end

of cylinder 1 across its base and the inner 55 end of the barrel 3.

According to my present invention I provide the barrel 3 with a key slot 8, the side portions of which are offset from the central portion, and the cylinder 1 with diametrically opposing sets of tumbler pins 9 in alinement with the offset side portions of the slot 8. The key, as shown in Fig. 6, is of conformable shape, having the irregular tumbler pin-engaging edges 10 of its shank 65 offset from the central portion 11 thereof. Thus the specified shape of the barrel slot provides for two series of tumbler pins, rendering it doubly difficult to pick, and further renders more difficult the insertion of an instrument with which to manipulate the tumbler pins. I further provide the cylinder 1 with a longitudinal slot extending through its periphery and its flange 2, in which is located a locking pin 12, of such 70 thickness as to project beyond the cylinder periphery and engage partly within a slot in the bolt cage 15 as shown in Fig. 2. The outer end of the pin 12 has a projection 13 to complete the broken cylinder flange 2, 75 while its inner end is provided with a cut-out portion 14 within which, as shown, the bolt sweep 6 engages in the normal (locked) position of the device, and as shown in Fig. 2. Thus the cylinder locking pin 12 may 80 not be withdrawn, and said cylinder consequently may not be rotated to remove the same until the proper key is inserted in the barrel, and turned to move the bolt sweep 6 out of the locking pin's slot 14. 90

Having thus described my invention, I claim,

In a lock of the character described, the combination of a cylinder provided with a peripheral slot, a barrel rotatable within 95 said cylinder, a bolt sweep actuated by said barrel, and a locking pin disposed within, and projecting beyond, the said cylinder slot and provided with a cut-out portion within which the bolt sweep engages in the locked 100 position.

In testimony whereof I affix my signature, in presence of two witnesses.

BERNHARD SUMMERFIELD.
